Primary Examiner — Elizabeth J Oswecki(74) Attorney, Agent, or Firm — Dale J. Ream(57) CLAIM

The ornamental design for a spiked footwear, as shown and described.

DESCRIPTION

FIG. 1 is a perspective view of a spiked footwear showing my new design;

FIG. 2 is a right side view thereof;

FIG. 3 is a left side view thereof;

FIG. 4 is a front view thereof;

FIG. 5 is a back view thereof;

FIG. 6 is a top view thereof; and,

FIG. 7 is a bottom view thereof.

The broken lines in the drawing view of FIG. 7 represent portions of the spiked footwear that form no part of the claimed design.
